UNITED STATES PATENT OFFICE.

CHARLES WALTERS, OF NEW YORK, N. Y.

DESIGN FOR A CIGAR-CASE.

SPECIFICATION forming part of Design No. 23,579, dated August 21, 1894.

Application filed June 2, 1894. Serial No. 513,322. Term of patent 7 years.

To all whom it may concern:

Be it known that I, CHARLES WALTERS, a subject of the Queen of Great Britain, residing at New York city, New York, have invented and produced a new and original Design for Cigar-Cases, of which the following is a specification, reference being had to the accompanying drawings, in which—

Figure 1 is a perspective view of my improved cigar case showing it open. Fig. 2 is a cross section of the closed case on line 2, 2, Fig. 1.

The leading feature of my design consists of a cigar case having an upper and lower section, of which one has a series of large parallel corrugations extending from end to end, while the other has a series of smaller

and shorter parallel corrugations and a flat section.

a, b, are an upper and lower section of the cigar case. The surface *a*, is provided with a series of parallel corrugations *a'*, extending from end to end and having a scalloped edge *a²*. The surface *b*, is provided with a series of shorter and narrower parallel corrugations *b'*, a scalloped edge *b²*, and a flat section *b³*.

What I claim is—

The design for a cigar case, substantially as shown and described.

CHARLES WALTERS.
